TWINE HOLDER

Filed Jan. 25, 1927

Inventor:
Thomas P. Harris
by Dring & Hague, Attorneys.

UNITED STATES PATENT OFFICE.

THOMAS P. HARRIS, OF CLARINDA, IOWA.

TWINE HOLDER.

Application filed January 25, 1927. Serial No. 163,399.

The object of my invention is to provide a 21 rotatively mounted therein. The said 55 twine holder of simple, durable and inexpensive construction, which may be made entirely of stamped sheet metal.

More specifically it is the object of my invention to provide a twine holder having means whereby comparatively short pieces of 60 twine from packages and the like may be wound on a suitable windlass so that the twine 10 may be again used at any time. The windlass is mounted in a comparatively tight casing to 65 protect the twine from dust and dirt.

A further object is to provide in a twine 70 holder having a windlass improved means for 15 retarding the rotation of said windlass as the twine is removed therefrom.

My invention consists in the construction, 75 arrangement and combination of the various parts of the device, whereby the objects 20 templated are attained, as hereinafter more fully set forth, pointed out in my claims, and illustrated in the accompanying drawings, in 80 which:

Figure 1 is a front view of my improved 25 twine holder.

Figure 2 is an end elevation of the same 85 showing the manner in which it is mounted to a wall.

Figure 3 is a detail sectional view taken on 30 the line 3—3 of Figure 1.

Figure 4 shows the blank sheet from which the body portion of the holder is formed.

Figure 5 is a longitudinal sectional view of 90 the windlass and the crank for operating the 35 same.

My improved twine holder comprises a body 95 portion 10 formed from a single piece of sheet metal laid out in the manner shown in Figure 4, and comprises substantially a rectangular 100 portion 11 having laterally extending portions 12, which form the ends of the casing. The rectangular portion 11 is divided into sections 13, 14, 15 and 16. Section 13 forms the 105 bottom of the casing which is provided with 45 an opening 17, while section 14 forms the front 110 which is provided with an elliptical bead 18 for ornamental purposes. Section 15 forms 115 the top, and section 16 forms the upwardly 120 projecting back section which is also provided 125 with an ornamental bead 19. The back 16 is 130 designed to provide suitable place for advertisements.

Each of the end members 12 is provided 135 with an opening 20 for receiving a windlass

21 rotatively mounted therein. The said 55 windlass is also formed of a single piece of sheet metal folded in tubular formation. One 60 end of the member 21 is provided with outwardly projecting lugs 22 which serve to engage 65 the ends of the body portion to prevent longitudinal movement of the windlass. The 70 other end of the windlass 21 is provided with a crank 23 also formed of pressed sheet metal. Said crank has a depression 24 for receiving the operator's finger. Said depression forms 75 an inwardly projecting knob 25 designed to engage the end of the body portion and to create a frictional contact therewith to retard 80 the rotation of the windlass. The central portion of the windlass is provided with 85 openings 26 for receiving one end of twine to be wound on said windlass, which may be inserted through the opening 17 in the bottom of the body portion, after which the windlass may be rotated by placing the operator's finger in the depression 24 and imparting 90 rotation to said windlass. The free end of the twine may be left projecting through the opening 17 so it may be grasped and any amount removed by simply pulling 95 the twine outwardly through said opening. The crank 23 is provided with a certain amount of spring tension to cause frictional engagement between the member 25 and the end of the body portion to prevent spinning of 100 the windlass as the twine is removed.

A suitable opening 27 may be provided in the back member 16 to provide means whereby the body portion may be suspended from a nail or the like in a wall.

Thus it will be seen that I have provided 105 a twine holder of simple, durable and inexpensive construction, which may be constructed entirely from thin sheet metal by the stamping process, and which is so constructed and arranged that a considerable amount of string may be accumulated on the windlass and retained in position for future use, and at the same time protected from dust and dirt.

I claim as my invention:

1. A twine holder comprising a body portion formed of a single piece of sheet metal having a bottom provided with a twine receiving opening, end, front and top members, the top being provided with a flat and upwardly projecting back member, a windlass rotatively mounted in said end members,

means for rotating said windlass, and means mounted on said windlass for fastening the end of twine thereto.

2. A twine holder comprising a support, a windlass rotatively mounted therein, said windlass being formed of tubular sheet metal, one end of said windlass being provided with outwardly projecting lugs for retaining the windlass against inward end movement, a crank on the opposite end of said windlass, said crank being formed of flexible material and provided at its outer end with means for engaging said support under slight pressure.

3. A twine holder comprising a support, a windlass rotatively mounted therein, said windlass being formed of tubular sheet metal, one end of said windlass being provided with outwardly projecting lugs for retaining the windlass against inward end movement, a crank on the opposite end of said windlass,

said crank being formed of flexible material and provided at its outer end with means for engaging said support under slight pressure, and means for detachably securing twine to said windlass.

4. A twine holder comprising a body portion formed of a single piece of sheet metal, a windlass rotatively mounted therein and formed of tubular sheet metal, one end of said windlass being provided with outwardly extending lugs to engage one side of said body portion, the opposite end of said windlass being provided with a flexible crank, the free end of said crank having inwardly extended bulged portion provided with a finger receiving depression for engaging said body portion, and means for detachably securing twine to said windlass.

Des Moines, Iowa, January 15, 1927.

THOMAS P. HARRIS.
